(57) **CLAIM**

The ornamental design for a nozzle device as shown and described.

DESCRIPTION

FIG. 1 is a right-front perspective view of a nozzle device in accordance with my design;

FIG. 2 is a left-front perspective view of the nozzle device of FIG. 1

FIG. 3 is a front elevational view of the nozzle device;

FIG. 4 is a top plan view thereof;

FIG. 5 is a right side elevational view thereof;

FIG. 6 is a left side elevational view thereof;

FIG. 7 is a rear elevational view thereof; and,

FIG. 8 is a bottom plan view thereof.

The broken line showing a nozzle device is included for the purpose of illustrating portions of the article and forms no part of the claimed design.

1 Claim, 8 Drawing Sheets
